O. E. OLESON

COMBINED WATER COLUMN AND LIQUID LEVEL GAUGE

Filed Aug. 16, 1920

INVENTOR
OLAF E. OLESON.
By *Albert C. Bee*
ATTORNEY

UNITED STATES PATENT OFFICE.

OLAF E. OLESON, OF CHICAGO, ILLINOIS.

COMBINED WATER COLUMN AND LIQUID-LEVEL GAUGE.

Application filed August 16, 1920. Serial No. 403,775.

To all whom it may concern:

Be it known that I, OLAF E. OLESON, a citizen of the United States, residing at Chicago, in the county of Cook and State of Illinois, have invented a new and useful Improvement in Combined Water Columns and Liquid-Level Gauges, of which the following is a specification.

My invention relates to an improved extended water column adapted for use in connection with boilers for making steam which, from their construction and size are necessarily set so high from the floor of the fire room that the water level in the boiler can not readily be observed from the floor by means of the ordinary level indicating devices, for example the ordinary water glass or gauge. In connection with boilers of the kind referred to it is not uncommon to have the water level twenty-five or thirty feet from the floor of the fire room and my invention provides devices controlled by the actual water level, for indicating through a downwardly extending column, the water level at a point where it may be conveniently read by the fireman without leaving the floor of the boiler room. My invention is also particularly adapted for use in connection with high pressure boilers, where the pressures are so high that ordinary float devices would fail to stand up under the pressures employed. By my invention I am able to make the float mechanism substantial enough to resist the highest pressures developed in steam boilers of the water level type.

In connection with my invention I find it desirable to employ a counterweight and gearing connecting it with the float mechanism to compensate in part for the weight of the float mechanism and the indicating devices connected therewith. By my invention I also provide the extended column with automatic devices for closing the column in case of accident to the sight glass at its lower end, which devices may be operated by a testing valve provided for that purpose, when desired to determine that the protective devices are in working order. I also provide pressure equalizing devices by which the pressure in the column above and below said automatic devices may be equalized to restore the float mechanism to its operating condition, when the column is again in working condition, or after one of said tests.

My invention will best be understood by reference to the accompanying drawing, in

which a boiler is shown diagrammatically at 10, and has water connections 11 and 12 with a float chamber 13. The chamber 13 has connected with its lower end a downwardly extending water column 14, in the lower end of which a sight glass 15 is secured. Intermediate the ends of the column 14 a valve housing 16 is connected, having a vertical opening 17 through it so that the vertical passage in the water column is uninterrupted by said valve housing. The housing 16 in its upper portion is provided with a valve seat 18, below which a relief passage 19 is formed and controlled by a valve 20 so that said relief passage may be connected when desired with a discharge or drain pipe 21. The housing 16 is also provided with a by-pass 22 extending from above the valve seat 18 to the column below said valve seat, this by-pass being controlled by a valve 23 by which the by-pass may be opened or closed as desired.

The chamber 13 contains a float 24 to the lower part of which a downwardly extending rod 25 is secured, which rod extends through the entire length of the column 14, through the valve housing 16 and terminates back of or within the sight glass 15. An indicating scale 26 may be mounted adjacent the sight glass 15 so that the position of the lower end of the rod 25, or a convenient mark upon said rod may indicate the position of the float 24 vertically and thus the level of the water in the boiler. A valve 27 is connected with the lower end of the column to drain the column when desired.

The float 24 has extending upwardly therefrom a rack 28 meshing with a gear 29, which gear on its opposite side meshes with a second rack 30 contained in a tubular vertical housing 31 and carries at its lower end a counterweight 32. Guide rollers 33 and 34 are preferably employed to retain the racks 28 and 30 respectively in mesh with the gear 29. The racks and gearing described are contained as indicated in an enclosing housing formed in part of the tubular housing 31 and in part of a similar housing 35 for the rack 28 and a connecting portion for enclosing the gear 29, this housing being wholly enclosed and connected with the upper end of the chamber 13 in any desired way as for example by means of a flange connection as indicated.

For the sake of permanency and reliability, the float 24 is preferably made of

metal and to withstand the high pressures used in many boilers the walls of the float must necessarily be of considerable thickness to prevent the float from collapsing. In any event, whether the float be so constructed or not the weight of the float and of the rod 25 is so large, particularly where the water level is twenty-five or thirty feet from the fire room floor, that the float alone cannot be depended upon to indicate the water level without resorting to prohibitive proportions of the float. For this reason I find it desirable to employ the counter-weight 32 to counterbalance a part of the weight of the float 24 and rod 25. By using this construction the float may readily be made sufficiently substantial to withstand high pressure and the buoyant effect of the float acting upon the unbalanced portion of the weight directly connected with the float, is sufficient to positively and accurately move the rod 25 so that its lower portion will afford a true indication of the water level in the boiler.

It will be noted that all of the gearing and parts connected with the counterbalancing mechanism are entirely enclosed and that there is no need for stuffing boxes of any kind in connection with said mechanism.

To automatically shut off the flow of water from the column 14 in case of accident, as for example breakage of the glass 15, the rod 25 is provided above the valve seat 18 with a valve 36 which, when the float 24 drops, engages the valve seat 18 and interrupts communication between the upper and lower parts of the column 14. This action results from the rush of water through the column due to relieving the pressure on its lower end below the valve seat 18. To test the apparatus, the same condition may be created by opening the valve 20, for which condition the operation of the rod 25 as viewed through the sight glass 15 and the flow of water through the drain pipe 21 affords a positive indication of whether the mechanism is in proper working order. When the valve 36 has been thus brought into engagement with its valve seat for any reason, it would remain there unless the pressure in the lower part of the column 14 were again brought up to the pressure in the upper part of the column and this condition may be established by opening the valve 23. When the pressures in the upper and lower parts of the column have been equalized in this manner, the buoyant effect of the float asserts itself and the rod 25 is lifted to move the valve 36 away from its seat, after which the valve 23 is closed, which is the normal condition of said valve for proper operation of the level indicating devices. My invention thus provides a means for automatically stopping the escape of water from the boiler and also for pre-

venting loss of pressure in the boiler in case of accident, as for example, breakage of the sight glass 15, or the lower part of the water column and provides in addition, means for reestablishing operative conditions of the float mechanism after the damage has been repaired.

It will be understood that the parts described may be constructed in any desired manner to meet the requirements of any particular case and that the parts may be connected and mounted in any desired manner known to the art; for example, the housing containing the counterweight mechanism may be made in any convenient manner to permit assembling the parts and have a removable cover plate to permit inspection and repair if desired. It will further be understood that I do not limit myself in carrying out my invention to the particular embodiment shown and described as I may employ equivalents thereof known to the art at the time of the filing of this application without departing from the scope of the appended claims.

What I claim is:

1. In a device of the class described, the combination of a float chamber for connection with a boiler, a float in said chamber to respond to water level therein corresponding with the water level of the boiler, said chamber having a lateral compartment extending therefrom in open communication with said chamber and extending vertically above and below said float in parallel relation with said float chamber, said chamber and compartment comprising a single receptacle having continuous and imperforate walls completely enclosing the same and having exterior communication only through said boiler connections, a counterweight in said vertical extension, toothed rods or racks projecting upwardly from said float and counterweight, a gear contained in said compartment engaging said toothed rods or racks, a tube extending downwardly from said chamber and having a transparent wall at its lower portion, and an indicating rod extending downwardly from said float through said tube to indicate the level of said float through said transparent wall.

2. In a device of the class described, the combination of a float chamber for connection with a boiler, a float in said chamber to respond to water level therein corresponding with the water level of the boiler, said chamber having a lateral compartment extending therefrom in open communication with said chamber and extending vertically above and below said float in parallel relation with said float chamber, said chamber and compartment comprising a single receptacle having continuous and imperforate walls completely enclosing the same and having

exterior communication only through said boiler connections, a counterweight in said vertical extension, toothed rods or racks projecting upwardly from said float and counterweight, a gear contained in said compartment engaging said toothed rods or racks, a tube extending downwardly from said chamber and having a transparent wall at its lower portion, an indicating rod extending downwardly from said float through said

tube to indicate the level of said float through said transparent wall, and a valve member carried by said indicating rod for closing said tube above said transparent wall when said float descends below a predetermined lower position.

In witness whereof, I hereunto subscribe my name this third day of August, A. D. 1920.

OLAF E. OLESON.
